UNITED STATES PATENT OFFICE.

JAMES R. PUTNAM, OF WATERBURY, CONNECTICUT, ASSIGNOR TO WATERBURY CLOCK CO., OF WATERBURY, CONNECTICUT, A CORPORATION.

INTERMITTENT AND LONG ALARM CLOCK.

1,110,714.

Specification of Letters Patent.

Patented Sept. 15, 1914.

Application filed May 7, 1914. Serial No. 836,941.

To all whom it may concern:

Be it known that I, JAMES R. PUTNAM, a citizen of the United States, residing at Waterbury, in the county of New Haven and State of Connecticut, have invented a new and useful Improvement in Intermittent and Long Alarm Clocks; and I do hereby declare the following, when taken in connection with the accompanying drawings and the characters of reference marked thereon, to be a full, clear, and exact description of the same, and which said drawings constitute part of this application, and represent, in—

Figure 1 a view in front elevation of an alarm clock constructed in accordance with my invention, its case simulating a large watch. Fig. 2 a view thereof in rear elevation, with the back of the case and the bell removed, with the pendant in vertical section and the adjacent part of the annular case-body broken away, the parts of the movement being shown in position for repeating or intermittently sounding the alarm. Fig. 3 a view of the clock in rear elevation with the back of the case and the bell removed and the parts shown in position for sounding a long or continuous alarm. Fig. 4 a corresponding view with the parts in position for shutting off the alarm. Fig. 5 a plan view of the clock with the pendant shown in horizontal section on the line *a—b* of Fig. 1. Fig. 6 a view of the clock in vertical central section. Fig. 7 a detached plan view of the alarm-converting cam, together with the operating-arm (shown in transverse section) of the alarm-converting lever, the said arm being entered into the notch of the cam as required for sounding an intermittent alarm. Fig. 8 a corresponding view with the arm engaged with the edge of the cam as required for sounding a long or continuous alarm. Fig. 9 a detached perspective view of the alarm-converting lever. Fig. 10 a detail sectional view of the lower end of the plunger, showing the method of mounting the alarm-converting cam upon it.

My invention relates to an improvement in that class of small portable alarm clocks known to the trade as "nickel alarms" and adapted to be adjusted or converted to sound a long continuous alarm or a short intermittent alarm, as desired, the object of my present invention being to produce a

simple and reliable alarm clock of the character described in which the conversion of the clock for sounding a continuous or an intermittent alarm is effected through an alarm-converting member mounted in the case directly above the movement.

With these ends in view my invention consists in a convertible alarm-clock having certain details of construction and combinations of parts as will be hereinafter described and pointed out in the claims.

In carrying out my invention as herein shown, I employ a case designed to represent a greatly enlarged watch and consisting, as shown, of an annular band or case-body 2, a removable back 3, and a hollow pendant 4 applied to the center of the top of the case-body 2, furnished with a pivotal bow 5, and mounting a rotatable and vertically movable plunger or stem 6 held in place by means of a retaining-pin 7 passing transversely through it and engaging with the inner face of the case-body 2. At its upper end the said stem is furnished with a hollow watch-crown 8 while its lower end is furnished with a shouldered screw 9 for the reception of an extension 10, the lower end of which is beveled as at 11. Between the stem 6 and extension 10, I interpose an alarm-converting cam 12 circular except for being furnished with a notch 13. The said stem 6, crown 8, extension 10 and cam 12 together form the alarm-converting member of my improved clock when embodied, as herein shown, in a case simulating a watch-case. In the event, however, of embodying my improved clock in a case of different design, the alarm-converting member would assume a different form, though its function would remain the same.

The notch 13 of the cam 12 receives the upwardly extending operating-arm 14 of a highly specialized part which for convenience I shall call the "alarm-converting lever" 15 located between the front and rear movement plates 16 and 17 and mounted upon a rock-shaft 18 encircled by a helical spring 19 exerting a constant effort to maintain the inner edge of the said arm 14 in contact with the edge of the cam 12. The said alarm-converting lever 15 is formed with an alarm-shut-off stop-finger 20 and an intermittent alarm stop-finger 21, located one above the other in the same vertical plane and separated by a long-alarm

clearance-slot 22 which permits the passage between the upper finger 20 and the lower finger 21 of a stop-pin 23 mounted in the escapement or crown-wheel 24 of the alarm-train which may be of any improved construction and is not shown in detail herein. The said wheel 24 co-acts with an ordinary verge or pallet 25 mounted upon a rock-shaft 26 carrying a hammer-arm 27 and hammer 28. The said lever 15 is also provided with an inclined inwardly bent shut-off arm 29 presenting an inclined surface to the extension 10 of the stem 6. The said lever 15 is also provided with a long downwardly depending intermittent-alarm arm 30 formed at its lower end with a finger 31 which co-acts with an intermittent-alarm cam-wheel 32 mounted upon the arbor 33 of the third wheel 34 of the time-train which may be of any approved construction and arrangement.

To limit the rotation of the stem 6, the same is provided with a stop-pin 35 located within the hollow crown 8 and mounted in an arm 36 secured to the stem, the lower end of the pin 35 entering a segmental slot 37 in a disk 38 acting as a closure for the upper end of the hollow pendant 4. The said disk 38 is furnished with spring fingers 39 engaging with the stem 6 to frictionally hold the same in its place against undue freedom of rotation or endwise movement. As shown, the movement is provided with a dial 40 having an alarm-setting circle 41 and a seconds circle 42.

To carry out the watch-design of the case, it is provided, as shown, with a concavo convex crystal 43 mounted within the forward edge of the case-body 2 which is supported, as shown, upon a pair of bracket-like feet 44. The front of the pendant 4 is provided with the word "Alarm" placed so as to be exposed by the crown 8 as shown in Fig. 1, when the stem 6 is lifted to make the clock an alarm-clock. On the other hand, when the stem 6 is crowded inward as shown in Fig. 4, for the shutting off of the alarm mechanism altogether, the lower edge of the crown 8 entirely covers and conceals the word "Alarm" upon the pendant. Below the said word "Alarm" on the front of the pendant, are placed the words, "Long" and "Repeat", located one above the other and accompanied by arrows indicating the direction in which the crown must be turned for converting the clock from a long alarm to an intermittent alarm and vice versa.

When the stem 6 is lifted for the clearance of its extension 10 from the alarm-shut-off arm 29 of the lever 15, the spring 19 will assert itself to turn the shaft 18 so as to swing the lever 15 from left to right, looking from the rear of the clock, whereby the edge of the arm 14 of the said lever 65 is allowed to co-act with the alarm-convert-

ing cam 12. Now according to the position of the notch 13 of the cam 12 with respect to the arm 14, the clock will sound a long or a short alarm. Thus if the notch 13 is registered with the arm 14, the same will enter the notch as shown in Figs. 2 and 7 which will permit the spring 19 to rock the shaft 18 so as to bring the alarm-stop finger 21 of the lever 15 into position to co-act with the stop-pin 23 in the wheel 24. The time-train by rotating the intermittent-alarm cam-wheel 32 now periodically rocks the lever 15 through its arm 30 so as at regular intervals to disengage the finger 21 from the stop-pin 23, whereby an intermittent alarm 80 will be sounded.

To convert the clock into a long or continuous alarm, the crown 8 is rotated through the distance represented by the length of a segmental slot 37 whereby the alarm 14 is compelled to ride out of the notch 13 in the cam 12, thus positively rocking the lever 15 just enough to register its long-alarm clearance-slot or space 22 with the path of the pin 23 so that when the alarm-train is once released it will continue to run and sound the alarm until it is stopped by the running down of the alarm-spring, or by the manual crowding down of the stem 6 into its alarm shut-off position in which it is shown in Fig. 4.

By means of my improvement, the clock is converted from a long alarm clock to an intermittent alarm clock and vice versa, and shut off altogether, by the manipulation from the outside of the clock of a single alarm-controlling member in place of two or more switches which have commonly been employed for the purpose in prior practice. In the embodiment of my invention, as herein shown and described, in an alarm clock designed to simulate a big watch, the alarm-controlling member has taken the form of a winding-and-setting stem, but this is a question of design and the said controlling member might be given another form without in any way changing its essential character or function.

I claim:—

1. In a convertible alarm-clock, the combination with the case thereof, of an alarm-mechanism convertible for sounding an intermittent alarm or a long alarm and adapted to be shut off altogether, and an alarm-controlling member mounted in the said case and coacting with the said alarm-mechanism for shutting it off altogether or causing it to sound a long or an intermittent alarm, or vice versa.

2. In a convertible alarm-clock, the combination with the case thereof, of an alarm-mechanism including an alarm-converting lever, and an alarm-controlling member mounted in the said case, co-acting at its inner end with the said lever and projecting

at its outer end through the case for manual operation, whereby the said lever may be positioned to shut off the alarm altogether or for the sounding of an intermittent 5 alarm, or a long alarm, or vice versa.

3. In a convertible alarm-clock, the combination with the case thereof, of an alarm mechanism including an alarm-converting lever, a rotary alarm-controlling member 10 mounted in the said case and, an alarm-converting cam mounted upon the said rotary alarm-controlling member and co-acting with the said lever for positioning the same for the sounding of an intermittent 15 alarm, or a long alarm, or vice versa.

4. In a convertible alarm-clock, the combination with the case thereof, of an alarm-mechanism including an alarm-converting lever provided with an operating-arm, an 20 alarm-shut-off finger, an intermittent-alarm finger, a shut-off arm, and an intermittent-alarm arm; and a longitudinally movable and rotatable alarm-controlling member mounted in the clock-case and co-acting 25 with the said operating-arm and with the said shut-off arm of the said lever.

5. In a convertible alarm-clock, the combination with the case thereof, of an alarm-mechanism including an alarm-converting 30 lever, a longitudinally movable and rotatable alarm-controlling member mounted in the said case and provided at its inner end with a cam co-acting with the said lever for positioning the same for the sounding of 35 an intermittent alarm, or a long alarm, and vice versa.

6. In a convertible alarm-clock, the combination with the case thereof, of an alarm-mechanism including an alarm-converting 40 lever, and a rotatable and longitudinally movable stem mounted in the clock-case and provided at its inner end with an alarm-converting cam engaging with the said lever for rocking the same and the said stem also 45 engaging with the said lever for rocking the same.

7. In a convertible alarm-clock, the combination with the case thereof, of a time-train, an alarm-mechanism including an 50 alarm-converting lever adapted to be peri-

odically oscillated by a member of the time-train for sounding an intermittent alarm, a longitudinally movable and rotatable stem co-acting with the said lever for positioning the same in its alarm-shut-off position and 55 provided with a cam co-acting with the said lever for positioning the same in its long and short alarm positions, and means for limiting the longitudinal and rotatable movement of the said stem. 60

8. In an alarm-clock, the combination with the case thereof, of a time-mechanism, an alarm-mechanism including a wheel carrying a stop-pin, an intermittent alarm-wheel driven by the said time-mechanism, 65 an alarm-converting lever provided with fingers respectively coacting with the said stop-pin, with an intermittent-alarm arm co-acting with the said wheel, with an operating-arm and with a shut-off arm; and a 70 longitudinally movable and rotatable stem provided with a cam co-acting with the said operating-arm for positioning the said lever and adapted at its inner end to co-act directly with the said shut-off arm, also for 75 positioning the said lever.

9. In an alarm-clock, the combination with the case thereof, of an alarm-mechanism including an alarm-converting lever, and a manually operable alarm-converting 80 stem mounted in the said case and longitudinally movable and rotatable therein for co-action with the said lever to position the same for shutting off the alarm-mechanism altogether and for sounding an intermittent 85 or a long alarm or vice versa, the said stem being provided at its inner end with a removable extension and with a converting-cam adapted to be independently engaged 90 with the said lever and the said cam being interposed between the lower end of the said stem and its said extension.

In testimony whereof, I have signed this specification in the presence of two subscribing witnesses.

JAMES R. PUTNAM.
